UNITED STATES PATENT OFFICE.

EDWARD E. HEDGES, OF NEW YORK, N. Y.

PROCESS OF DISTILLING SHALE.

1,428,716.

Specification of Letters Patent. Patented July 25, 1923.

Application filed June 13, 1921, Serial No. 477,293. Renewed April 8, 1922. Serial No. 550,795.

To all whom it may concern:

Be it known that I, EDWARD E. HEDGES, a citizen of the United States, residing at New York, in the county of New York and State of New York, have invented certain new and useful Improvements in Processes of Distilling Shale, of which the following is a specification, reference being had therein to the accompanying drawings.

10 This invention relates to a process of treating kerogen shales for the recovery of the valuable constituents thereof, especially, though not exclusively, the hydrocarbon content, but also as a secondary desideratum, 15 water-soluble potash, ammonia, which may be converted into ammonium sulphate, fixed gases which may be employed for illuminating and heating purposes, and perhaps other minor constituents which may be recovered 20 and utilized or converted into valuable by-products by subsequent processing.

It is well known that there are a considerable number of oil shale deposits in various parts of the world and that the different 25 deposits represent different qualitative and quantitative structures. Not all shales contain hydrocarbons which can be liberated in the form of hydrocarbon oils, but the present invention is directed particularly to kerogen 30 shales which do contain hydrocarbons in great quantities, which, by the proper treatment, may be liberated in the form of hydrocarbon oils analogizing crude well oils, as found in petroleum fields. Many attempts 35 have been made to release the hydrocarbons from the shale, such attempts having been more or less successful, but the present invention has for an object to provide a process which will liberate substantially all of 40 the hydrocarbon content in the form of oils analogizing well oils, together with such other constituents of value as may be found in said shales, the residuum being a spent shale which may be utilized to form a base 45 for manufacturing cements, or for many other purposes, but the further use of such spent shale forms no part of the present process.

The present invention resides in introducing the raw shale, at atmospheric temperature, at one end of a retort, preferably of the rotating tubular type, but not necessarily limited thereto, the requirements being a sufficient agitation and cascading of the shale, the term "cascading" comprehending

the raising of the shale or portions thereof and dropping from such raised position to a lower level and progression from the end of introduction to the end of discharge. The discharge end of the retort is heated to a 60 high temperature so that the shale, in progressing from the introduction end, at atmospheric temperature, is gradually heated and passes through areas of increasing heat. The gradual heating of the shale progressively 65 liberates the several constituent parts which are respectively liberated by the various temperatures and the gases so released are passed backwardly or toward the introduction end and discharged, so that the gases 70 as they are released pass through cooler areas instead of through hotter areas, being at no time subjected to heat greater than that of the area in which they are liberated.

At the end opposite the introduction end, 75 the spent shales are discharged and the end of the retort will, therefore, be referred to as the discharge end, it being understood that the discharge end is the end which is heated to the highest temperature. The heat at the 80 discharge end is sufficient to decompose steam which may be introduced into the retort saturated, at boiler temperature.

The drawings accompanying this application are shown merely for the purpose of 85 illustrating an apparatus which will carry out the invention, and are not intended in any way to limit the invention to the exact apparatus. In said drawings:

Figure 1 is a longitudinal diametrical sectional view through a rotating retort in which the process may be practised;

Figure 2 is a transverse sectional view through the driving and adjusting mechanism taken on line 2-2 of Figure 1;

Figure 3 is a transverse sectional view through the inlet worm seal, taken on line 3-3 of Figure 1, and

Figure 4 is a transverse sectional view through the retort, taken on line 4-4 of Figure 1.

Like characters of reference indicate corresponding parts throughout the several views.

As illustrated in the drawings, a retort is 105 employed there shown as a cylinder 10 mounted in any approved way to provide for rotation and adjustment on the idlers 11 and journal bearing 12. The idlers 11 are adapted to be raised and lowered for the purpose 110

of raising and lowering the cylinder 10, such raising and lowering means being shown conventionally as the screw 13. The journal bearing 12 is also mounted in an upright 14 which is mounted upon a ball-and-socket bearing 15 which permits the angular adjustment of the lower end of the retort when the idlers 11 are raised and lowered as above described.

10 The journal bearing 12 is hollow, as indicated at 16, preferably larger at its outer end than at the end adjacent the chamber of the retort, and a pipe 17 extends longitudinally and axially through said opening 16 which 15 is the discharge orifice of the retort.

The pipe 17 communicates by means of a joint 18 and pipe 19 with a steam generator 20 by the combination of which steam is introduced into the retort. The retort is rotated 20 in any approved manner, as by means of providing a gear 21 about the periphery of such retort adjacent the lower end intergeared with a pinion 22 which, in turn, is propelled by any approved type of motor, as indicated 25 at 23.

At the end opposite the outlet 16 a hopper 24 is provided having an inlet nozzle 25 communicating with a central chamber 26, forming a part of the inlet worm seal feed. 30 This seal feed comprises a partition 27 providing a volute passage from the central chamber 26 to the opening 28, whereby the rotation of the retort in the direction indicated by the arrow at Figure 3 will permit 35 the passage by gravity of material from the central chamber 26 through the volute passage to be discharged at 28 into the interior and at the bottom of the retort. A pipe 29 is introduced through the central chamber 40 26 and communicates with a condenser indicated conventionally at 30.

At the end opposite the inlet seal feed, a discharge seal feed is provided substantially identical with the inlet feed, comprising 45 a partition 31 having a volute passage 32 which takes up material at the bottom of the periphery of the retort and, by reason of the rotation, moves the said material upwardly to the central chamber 33 which 50 communicates with the discharge passage 16. The material is, therefore, introduced into and removed from the retort wholly by reason of the rotation of such retort and maintaining at all times a seal against the 55 introduction of air or the outlet of gases except through the passages provided for that purpose.

For the purpose of heating the shale in the retort some kind of heating element is 60 provided, preferably such as will provide heat at one end of the retort, preferably the lower end and preferably further graduated as to temperature. As shown in the drawing a spiral resistance coil 34 extends about the 65 interior of the retort and is in communica-

tion with the rings 35 and 36. Rolling contacts 37 and 38 conduct to these rings and from the rings to the resistance coil 34 electromotive force from the source 38'. A second resistance coil 39 is provided within 70 the retort adjacent the coil 34, communicating by means of similar rings 40 and 41 and similar rolling contacts 42 and 43 with a source of electromotive force 44. The two sources of electromotive force 38' and 44' 75 have been differentiated in the drawing to indicate different potentiality, whereby a current of greater voltage and higher amperage is provided to the coil 34 than that supplied to the coil 39. This is merely for 80 the purpose of indicating that the part of the retort at which the coil 34 is shown is hotter than that part at which the coil 39 is shown and varying the heat whether through the use of electric current and resistance element, or otherwise, may be employed for 85 the purpose.

In practising the process in an apparatus of the kind disclosed in the drawing, it will be obvious that the raw shale finely powdered will be introduced in the hopper 24 and passing through the chute 25 and inlet seal feed will be deposited in the interior of the rotating retort. The interior of the retort is heated as indicated, the lower end or that end farther from the inlet feed being heated to the greater temperature. It is obvious that the introduction of raw shale at atmospheric temperature continuously will maintain the inlet end of the retort in a more or less cooled condition and that the retort will be increasingly heated toward the other end. This is made possible from the fact that there is a comparatively small amount of displacement and replacement of gases within the retort, provision being made for the introduction of steam through the pipe 17 and the withdrawal of the gases through the pipe 29, other than which there is no passage of the gases longitudinally of the 100 retort. It is obvious that the shales, as they move from the inlet or cooler end toward the hotter end of the retort, as they will by reason of the rotation and inclination of the cylinder, will move gradually from the cooler 105 to the hotter areas, the several volatile substances contained in the shale being, of course, liberated from the shale at the various temperatures, and it is obvious also that those substances which are liberated at the 110 lower temperatures will be first liberated as the shale moves from the cooler to the hotter areas and that when liberated in gaseous form they will move always to and through the cooler areas to be discharged through the 115 pipe 29 to the condenser. As the shale progresses, therefore, from the cooler to the hotter end the several substances will progressively be liberated and volatilized, the gases 120 passing backwardly, or at all times through 125 130

the cooler areas to discharge. It is desirable in the practise of the process that the hotter end of the retort be much hotter than is necessary to release all the hydrocarbons from the shale, so that the shale as it reaches the hotter end contains fixed carbons in highly heated condition. The introduction of steam through the pipe 17 at boiler temperature, or at some superheated temperature which is unimportant to the present invention, immediately acts upon such fixed carbons and forms therewith water gas liberating hydrogen which passes backwardly to the cooler end through the progressively cooler areas attacking and commingling with the hydrocarbons previously liberated, adding hydrogen to the hydrocarbon molecules so that the number of light hydrocarbon molecules is increased over the number which would be liberated by dry distillation. The passing of the liberated hydrocarbons backwardly through the cooler areas prevents cracking and also prevents fixing of some of the gases which might otherwise become fixed gases when subjected to heat. It will be obvious also that there will be a difference in temperature between the gaseous content and the solid content at any given area, so that, while the gases liberated are passed backwardly, they are not at any time passed through an area so cool as to again condense the gases within the retort and are discharged in gaseous condition to the condenser.

There is a certain amount of fixed carbon in the shale after the hydrocarbons, nitrogen and the like have been released therefrom and the said shale containing said fixed carbon, when approaching the discharge or hotter end of the retort, is raised to such a temperature that the steam, thus introduced, acting upon this fixed carbon at high temperature, is decomposed into its elements, the oxygen combining with the carbons to form carbon monoxide, or carbon dioxide, the nascent hydrogen being free to combine with the hydrocarbon vapors, whereby a greater quantity of light hydrocarbon oils is produced; that is to say, the hydrocarbon vapors, as released by heat from the shale, take up the nascent hydrogen, or a part of such hydrogen, so that there are a greater number of hydrogen atoms in some of the hydrocarbon molecules than found in the hydrocarbon vapors as released by heat from the shale. Also the heating of the shale gradually to a high temperature, in the presence of the water vapor, releases a greater percentage of the hydrocarbons than can be done by dry heat,—in fact, releases practically all of the hydrocarbon oils, which pass over as vapors, passing successively from the area of release through cooler areas but the temperature in all of said areas being maintained sufficiently high to

prevent condensation, until the vapors pass over, and are discharged from the retort.

The vapors which pass over are complex and are first run through a condenser to condense the condensable portions thereof, 70 which consist largely of the hydrocarbon oils and ammonia-impregnated water. The fixed gases which pass over are, of course, not condensable and also contain some ammonia. The fixed gases are put through a 75 scrubber and are treated with sulphuric acid to release the ammonia therefrom, converting the same to ammonium sulphate, the fixed gases being thus scrubbed and freed from ammonia and are available for illuminating and heating purposes. The ammonia impregnated water is also treated with sulphuric acid to remove the ammonia from the water, converting the ammonia into ammonium sulphate. 85

The hydrocarbon oils condensed are analogous to the well oils and are similarly treated, refined and fractionated in a substantially similar manner.

There is no range of temperatures within 90 the retort which is at present known to be essential to the successful carrying out of this process. Apparently a temperature of from three to four hundred degrees Fahrenheit maintained at the introduction or cooler 95 end of the retort, with a temperature approximating 1400° Fahrenheit at the discharge or heated end of the retort will serve the purpose and will carry out all of the steps hereinbefore mentioned in the manner 100 described. The shale, after being discharged from the discharge or hotter end of the retort, still contains a considerable quantity of water-soluble potash, which is removed therefrom by leaching in substantially the 105 usual and ordinary manner, after which the residuum is available for the purpose of manufacturing cement when found desirable. The apparatus for carrying out the condensation, scrubbing and leaching may 110 be the usual and ordinary apparatus employed for such purposes, and the process as carried out in said apparatus may be the usual and ordinary process as generally employed therefor. In other words, the vapors 115 discharged from the cooler end of the retort, after so being discharged, may be treated in the usual and ordinary manner, no claim being made in this application to the further processing of the vapors, this invention residing in introducing the shale at the cooler end of a retort, increasing the heat throughout its length, passing the shale successively from cooler to hotter areas and the 120 liberated vapors from hotter to cooler areas, 125 and employing water vapor in contact with sufficiently heated fixed carbons to form water gas and liberate the hydrogen for acting upon and with the hydrocarbon vapors, as hereinbefore described. 130

What I claim to be new is:

1. The process of distilling oil bearing shale, consisting in introducing raw shale into one end of an elongated retort, moving the shale along the retort under constant agitation, maintaining heat within said retort varying from a temperature to drive off the most volatile ingredients at the end of introduction to a temperature to decompose water in the presence of carbon at the opposite end, conducting the released gases backwardly through progressively cooler areas, introducing steam into contact with the heated fixed carbon residuum at the hotter end, commingling the gases released by decomposition with the released volatile gases, and discharging the spent shale residuum from said hotter end.

2. The process of distilling oil bearing shale, consisting in introducing the raw shale into one end of an elongated retort, substantially without air, moving the shale along the retort under constant agitation, maintaining heat within said retort varying from a temperature to drive off the most volatile ingredients at the end of introduction to a temperature to decompose water in the presence of carbon at the opposite end, conducting the released gases backwardly through progressively cooler areas, introducing steam into contact with the heated fixed carbon residuum at the hotter end, commingling the gases released by decomposition with the released volatile gases, and discharging the spent shale residuum from the hotter end substantially without admission of air.

3. The process of distilling oil bearing shale, consisting in introducing the raw shale continuously into one end of an elongated retort, substantially without air, moving the shale along the retort under constant agitation, maintaining heat within said retort varying from a temperature to drive off the most volatile ingredients at the end of introduction to a temperature to decompose water in the presence of carbon at the opposite end, conducting the released gases backwardly through progressively cooler areas, introducing steam into contact with the heated fixed carbon residuum at the hotter end, commingling the gases released by decomposition with the released volatile gases, and continually discharging the spent shale residuum from the hotter end substantially without admission of air.

4. The process of distilling oil bearing shale, consisting in introducing raw shale into one end of an elongated retort, moving the shale along the retort under constant

cascading action, maintaining heat within said retort varying from a temperature to drive off the most volatile ingredients at the end of introduction to a temperature to decompose water in the presence of carbon at the opposite end, conducting the released gases backwardly through progressively cooler areas and through the cascaded shale, introducing steam into contact with the heated fixed carbon residuum at the hotter end, passing the gases released by decomposition through the progressively cooler areas to unite with the volatile gases at release, and discharging the spent shale residuum from said hotter end.

5. The process of distilling oil bearing shale, consisting in introducing the raw shale into one end of an elongated retort, substantially without air, moving the shale along the retort under constant cascading action, maintaining heat within said retort varying from a temperature to drive off the most volatile ingredients at the end of introduction to a temperature to decompose water in the presence of carbon at the opposite end, conducting the released gases backwardly through progressively cooler areas and through the cascaded shale, introducing steam into contact with the heated fixed carbon residuum at the hotter end, passing the gases released by decomposition through the progressively cooler areas to unite with the volatile gases at release, and discharging the spent shale residuum from the hotter end substantially without admission of air.

6. The process of distilling oil bearing shale, consisting in introducing the raw shale continuously into one end of an elongated retort, substantially without air, moving the shale along the retort under constant cascading action, maintaining heat within said retort varying from a temperature to drive off the most volatile ingredients at the end of introduction to a temperature to decompose water in the presence of carbon at the opposite end, conducting the released gases backwardly through progressively cooler areas and through the cascaded shale, introducing steam into contact with the heated fixed carbon residuum at the hotter end, passing the gases released by decomposition through the progressively cooler areas to unite with the volatile gases at release, and continually discharging the spent shale residuum from the hotter end substantially without admission of air.

In testimony whereof I hereunto affix my signature.

EDWARD E. HEDGES.
